RECEPTACLE

Frank C. Ziegler, Tulsa, Okla.

Application August 8, 1949, Serial No. 109,121

4 Claims. (Cl. 220—57)

1

This invention relates in general to receptacles, and deals, more particularly, with an improved receptacle fastening means for providing a releasable lock of the cover or lid of a receptacle in closed position to prevent accidental or unintended opening thereof.

The receptacle closure and fastening means of the present invention is one of general utility in that it may be readily employed in a wide range and variety of applications and uses in connection with practically any receptacle having a closure or lid which is pivoted or otherwise separable from the body of the receptacle.

A primary object of the invention, accordingly, is to provide such a receptacle closure and fastening means of general utility in a simplified and inexpensive construction and arrangement which may be readily provided as a unitary part of any suitable receptacle at low cost and with little or no change in the structure of the receptacle.

Another primary object of the invention is to provide a receptacle closure and fastening means such as described in which the fastening means comprises a pivoted locking arm that is operable easily and quickly and readily secured in a simple snap fastening action to provide a positive lock of the receptacle cover or lid in closed position.

A further object of the invention is to provide a receptacle closure and fastening means therefor wherein the fastening means comprises a locking arm which is pivotally connected to the receptacle body in overlying relation to the receptacle cover or lid in closed position and which is releasably secured in such position by a co-operating snap fastening means on the receptacle cover or lid.

An additional more specific object of the invention is to provide such a pivoted locking arm construction for a receptacle closure in which the snap fastening means on the closure comprises a pair of retaining elements adapted to clasp opposite edge portions of a plate-like portion on the locking arm in frictional snap fastened relation therewith.

Further objects and advantages, and other new and useful features in the construction, arrangement and general combination of elements and parts of the invention will be readily apparent as the following description proceeds with reference to the accompanying drawings, for purposes of illustration but not of limitation, in which like reference characters designate like parts throughout, and in which:

Fig. 1 is a top plan view of a receptacle pro-

2

vided with fastening means for the cover or lid thereof in accordance with the invention;

Fig. 2 is a front elevational view of the receptacle and closure locking means shown in Fig. 1;

Fig. 3 is a sectional view of Fig. 1 along line 3—3, looking in the direction of the arrows;

Fig. 4 is an end view of the receptacle as seen from the right of Fig. 1; and,

Fig. 5 is a top plan view corresponding to Fig. 1 showing the locking arm as released to permit the receptacle cover or lid to swing outwardly to open position as represented in broken lines.

The invention is shown in the drawings, for illustrative purposes only, as provided in a receptacle known as a pyx which is used for certain religious purposes. It will be understood that the invention is not in any way limited to such a receptacle but rather, is equally applicable to any similar or related type of receptacle such as a watch casing, compact or powder case, pill box, or any other similar container in the form of an article of jewelry, or the like. Likewise, while the invention is disclosed in connection with a pyx on which the design of a cross, as shown in Fig. 1, is most appropriate, it will be appreciated that in the case of various other receptacles, as aforesaid, there may be employed instead any selected emblem, charm, or similar plate-like ornament in the form of a medal or coin, or the like, carrying a symbol, character or other special or artistic design. In this regard, any suitable plate-like ornament having any selected design may be readily employed in accordance with the invention to serve a dual purpose as a unitary part or member of the receptacle locking means in addition to its usual value as an article of jewelry or ornament, or the like.

Referring now, more particularly, to the drawings, the invention is disclosed in connection with a receptacle or casing having a generally cylindrical construction but, of course, is also adaptable to any similar box or casing of square, rectangular, oval or other selected contour. In the present example, the receptacle is shown comprising a cup-shaped body portion 1 and a closure in the form of a cover, top or lid 3 having a peripheral skirt 4 and which is pivotally connected to the receptacle body 1 in any suitable manner as by a hinge 5.

On the receptacle body 1, a second independent hinge 10 is provided in any suitable location, preferably in a position opposite the cover supporting hinge 5 and below the peripheral skirt 4 of the cover or lid 3. The hinge 10 may be pro-

vided in any suitable way and, in the present example, is shown in the form of a small flat projecting piece 11 which is united to the outer wall of the receptacle body and which comprises a pair of spaced ears 12 having aligned horizontal holes for receiving the ends of a hinge pin 14 which is carried at one end of a locking arm 15.

The locking arm 15, provided with the hinge pin 14, is suitably formed to correspond substantially with the contour of the adjacent side and top of the closed receptacle and to overlie the cover 3, as best seen in Fig. 2. The locking arm 15, accordingly, includes a vertical side portion 16 merging into an intermediate portion 17 which extends in closely adjacent abutting relation to the cover or lid 3 in closed position and is thereby adapted to maintain said cover or lid 3 against accidental or unintended opening.

The locking arm 15 is thus provided of suitable length to overlie the over or lid of the receptacle 3, substantially as shown in Fig. 1, together with a plate-like ornament 20 emblem or charm, or the like, attached to the free end of said locking arm 15, preferably at a point in which the ornament is located at the approximate center area of the cover or lid 3.

The plate-like ornament 20 may be provided on the locking arm in any suitable manner either as an integral portion thereof, as shown, or in the manner of a separate medal or coin united thereto or a similar plate provided with a symbol, character or design, or, carrying an attached emblem, charm or other ornament or article of jewelry.

In the present example, the plate-like ornament 20 is shown in the form of a cruciform badge provided as an integral extension on the locking arm 15. In the closed position of the receptacle, as shown in Figs. 1 and 2, the plate-like ornament 20 is utilized to hold the associated locking arm 15 in locking position by engagement of the edge portions of said plate-like ornament with spaced retaining elements 25 provided on the outer surface of the cover or lid 3. Preferably, the spaced retaining elements 25 are provided by a bar 26 united to the lid or cover 3 and having the ends thereof bent upwardly to define said spaced retaining elements 25 in the form of tongues, tabs or similar projections, substantially as shown in Figs. 3 and 4. The arrangement is such that the spaced retaining elements 25 are adapted for a positive frictional engagement with opposite edge portions of the ornamental plate 20 and inasmuch as said retaining elements 25 are necessarily slightly resilient at their free ends, they operate with a slight snap action against the engaged edge portions of the ornamental plate 20 whenever said plate is either secured between said retaining elements or released therefrom.

As shown in Fig. 1, the completed receptacle with the cover or lid closed and the locking arm 15 in locking position, is compact and uniformly proportioned and provides a most pleasing artistic appearance by reason of the plate-like ornament 20 in the center area thereof.

The receptacle is easily and quickly opened by a simple pull on the exposed free end of the ornamental plate 20 or any similar force on the locking arm 15 which is sufficient to remove said plate 20 from engagement between the spaced retaining elements 25. The locking arm 15 including said plate 20 is then swung by pivotal movement on the hinge 10 to an outward position clear of the cover or lid 3, as shown in Fig.

5, whereupon said cover or lid 3 is free to be lifted from the receptacle body 1 and moved, in the usual manner, to its open position shown in broken lines in Fig. 5.

Likewise, the receptacle cover or lid 3 is readily closed in the usual manner, as shown in full lines in Fig. 5, whereupon the locking arm 15 is swung to overlying relation to said cover or lid 3, as seen in Figs. 1 and 2, and the locking arm secured in such position by engagement of the ornamental plate 20 with the spaced retaining elements 25 in a quick and easy snap fastening action, as aforesaid, which holds said locking arm 15 firmly and rigidly in locking position for all practical purposes. The locking arm 15, as thus secured, extends closely adjacent to the cover or lid 3 in abutting relation thereto and thereby positively maintains said cover or lid 3 in closed position and prevents any accidental or unintended opening thereof.

While the invention has been described in detail with a specific example, such example is intended as an illustration only inasmuch as it will be apparent that various modifications in the construction, arrangement and general combination of parts may be provided without departing from the spirit and scope of the invention. The present embodiment is therefore to be considered in all respects as illustrative and not restrictive, the scope of the invention being indicated by the appended claims rather than by the foregoing description, with all changes falling within the scope, meaning and range of equivalency of the claims intended to be embraced therein.

What is claimed and desired to be secured by United States Letters Patents is:

1. In a receptacle comprising a receptacle body and a cover having a hinged connection to said receptacle body, means for retaining said cover in closed position comprising an arm pivotally connected at one end to the receptacle body on the side opposite said hinged connection and adapted to swing from a position outwardly of said cover to a position overlying said cover, a plate rigidly connected to the other end of said arm and disposed in generally horizontal relation to said cover in closed position, and a pair of spaced outwardly projecting tongues on said cover, said tongues being so spaced as to engage opposite edges of said plate in said generally horizontal relation to said cover to retain said plate therebetween and thereby secure said arm in overlying relation to the receptacle cover.

2. In a receptacle comprising a receptacle body and a cover having a hinged connection to said receptacle body, means for retaining said cover in closed position comprising an arm pivotally connected at one end to the receptacle body on the side opposite said hinged connection and adapted to swing from a position outwardly of said cover to a position overlying said cover, a plate rigidly connected to the other end of said arm and disposed in generally horizontal relation to said cover in closed position, and a bar united to said cover having its ends bent to provide a pair of spaced outwardly projecting tongues, said tongues being so spaced as to engage opposite edges of said plate in said generally horizontal relation to said cover to retain said plate therebetween and thereby secure said arm in overlying relation to the receptacle cover.

3. In a receptacle comprising a receptacle body and a cover having a hinged connection to said receptacle body, means for retaining said cover

in closed position comprising an arm pivotally connected at one end to the receptacle body on the side opposite said hinged connection and adapted to swing from a position outwardly of said cover to a position overlying said cover, a plate in the shape of a cross rigidly connected to the other end of said arm and disposed in generally horizontal relation to said cover in closed position, and an outwardly projecting tongue on said cover engaging the end of an arm of said cross in its said generally horizontal relation to said cover in closed position.

4. In a receptacle comprising a receptacle body and a cover having a hinged connection to said receptacle body, means for retaining said cover in closed position comprising an arm pivotally connected at one end to the receptacle body on the side opposite said hinged connection and adapted to swing from a position outwardly of said cover to a position overlying said cover, a plate in the shape of a cross rigidly connected to the other end of said arm and disposed in generally horizontal relation to said cover in closed position, and a pair of spaced outwardly

projecting tongues on said cover, said tongues being so spaced as to engage the ends of a pair of oppositely extending arms of said cross in its said generally horizontal relation to said cover in closed position.
